UNITED STATES PATENT OFFICE

97,361

DESIGN FOR A TANDEM BIMOTORED MID-WING MONOPLANE

Oscar A. Swanson, Dayton, Ohio

Application July 18, 1935, Serial No. 57,713

Term of patent 3½ years

To all whom it may concern:

Be it known that I, Oscar A. Swanson, a citizen of the United States, residing at Dayton, in the county of Montgomery and State of Ohio, have invented a new, original, and ornamental Design for a Tandem Bi-Motored Mid-wing Monoplane, of which the following is a specification, reference being had to the accompanying drawing, forming part thereof, wherein

Fig. 1 is a top plan view of an airplane showing my new design;

Fig. 2 is a front elevational view of the said airplane design; and

Fig. 3 is a side elevational view of said airplane design.

It is to be understood that, that portion of the design shown in solid lines in the drawing is the dominant feature thereof.

I claim:

The ornamental design for a tandem bi-motored mid-wing monoplane, as shown and described.

In testimony whereof I affix my signature.
OSCAR A. SWANSON.
